UNITED STATES PATENT OFFICE.

HAROLD C. SUCKERT, OF NEW YORK, N. Y.

VACUUM FUEL-FEEDING SYSTEM FOR GASOLENE-ENGINES.

1,256,610.

Specification of Letters Patent. Patented Feb. 19, 1918.

Application filed August 27, 1915. Serial No. 47,596.

To all whom it may concern:

Be it known that I, HAROLD C. SUCKERT, a citizen of the United States, and a resident of the borough of Manhattan, city, county, and State of New York, have invented certain new and useful Improvements in Vacuum Fuel-Feeding Systems for Gasolene-Engines, of which the following is a specification.

- 10 In the installation of gasoline engines it has heretofore been the almost universal practice to place the gasoline or fuel tank above the carbureter in order to secure a gravity feed of the fuel from the tank to the carbureter. In the few instances in which the fuel tank has been placed below the carbureter some form of pump has been used to maintain an air pressure in the gasoline tank in order to force the gasoline up to the carbureter. In other cases a vacuum pump has been used to draw the gasoline from the fuel tank to a point higher than the carbureter and to then feed the gasoline by gravity to the carbureter. This invention relates to this latter type of fuel feeding means.

It is the main object of this invention to simplify the vacuum apparatus by means of which the gasoline is drawn from the supply tank and delivered into the small gravity tank from which it is fed to the carbureter.

Another object of the invention is to dispense with all float-operated devices and to provide an apparatus which will be very simple in construction and positive and reliable in operation.

Other objects and advantages of the invention will appear hereinafter.

40 In the drawings, Figure 1 is an outline view of my improved fuel feeding system applied to a gasoline engine;

Fig. 2 a vertical sectional view of the feed tank showing the parts in the position 45 which they occupy when gasoline is being drawn from the storage tank into the feed tank;

Fig. 3 a similar view showing the parts in the position which they occupy when 50 gasoline is being delivered from the pumping chamber into the feed tank;

Fig. 4 a vertical sectional view showing a

slightly modified form of the pumping apparatus; and

Fig. 5 a detail sectional view of the valve 55 for closing communication between the pumping chamber and the suction apparatus.

Referring to the various parts by numerals, 1 designates the engine, 2 the manifold 60 through which the gas from the carbureter is conducted to the engine intake; 3 the carbureter and 4 the fuel tank. The gravity feed tank 5 is located in any convenient position above the carbureter, preferably under the hood of the engine, as indicated in Fig. 1. The lower end of this gravity feed tank is connected by a pipe 6 to the carbureter, and through this pipe fuel is fed by gravity. The fuel tank 4 is connected 70 to the pumping apparatus through a pipe 7 and said apparatus is connected to the manifold of the engine through a pipe 8.

In the feed tank 5 is located a transverse partition 9, said partition dividing the tank 75 into a pumping chamber 10 and a feeding chamber 11, this latter chamber being connected to the carbureter by pipe 6. The partition forms the bottom of the pumping chamber 10 and a flap valve 12 controls communication between said chamber and the fuel feeding chamber; and the bottom wall 9 inclines downwardly to the discharge opening 13 controlled by the said valve. The upper end of the pumping chamber 10 is closed 85 by a cap 14 in which is formed a valve chamber 15. Opening into this chamber through the top wall thereof is a suction or exhaust port 16 and connected to this port is the suction pipe 8 leading from the engine. 90 Through the cap 14 is formed a vent 17, said vent being close to the exhaust port 16.

In the pumping chamber near the upper end thereof, is mounted a vertical compartment 18; and in said compartment is a pump 95 bucket 19, said bucket being maintained normally in its upper position by means of a spring 20 which supports said bucket. Pivotally connected to the upper end of the pump bucket is a lever arm 21, said arm being pivoted at 22 and carrying a valve arm 23. In the upper end of this valve arm is mounted a ball valve 24 which is pressed outwardly by a spring 25. This ball valve,

in the upper position of the pump bucket, closes the vent 17, as shown in Fig. 2, and in the lower position of the pump bucket the said arm is swung into position to close the port 16, as shown clearly in Fig. 3. The spring-pressed valve ball 24 serves as a yieldable latch or lock to hold the pump bucket in its positions. Secured to the compartment 18 and extending through the wall thereof is a siphon 26, the longer end of said siphon extending down into the pumping chamber, the shorter arm thereof extending into the pump bucket and near to the bottom thereof when the said bucket is in its upper position. The pump bucket is slotted at 27 to permit the bucket to move vertically.

The operation of the apparatus thus far described may be briefly set forth as follows: Assuming the pumping chamber to be emptied of gasoline, the parts will be in the position shown in Fig. 2, wherein the vent 17 is closed and the exhaust port 16 is open. When the engine is in operation there will be sufficient suction through pipe 8 to exhaust air from the pumping chamber 10, and this will result in a flow of gasoline through pipe 7, into the pumping chamber. Gasoline will be accumulated in the chamber 10, the suction through pipe 8 being sufficient to hold the flap valve 12 closed. Gasoline will rise in the siphon tube 26 and when the level thereof has reached the top of the siphon gasoline will flow into the pump bucket 19, filling the same up to the slot 27. The weight of the gasoline thus accumulated in the bucket will be sufficient to depress it and throw the valve 24 over to the port 16, thereby opening the vent and closing the exhaust port. As soon as the vent port is opened the flap valve 12 will open and permit the accumulated gasoline to flow into the feed tank. Gasoline from the pump bucket will be siphoned back into the feed tank and the said bucket will then be raised by spring 20, thereby returning valve 24 to the vent 17 so that the operation of drawing gasoline into the pumping chamber will be repeated.

In Fig. 4 is shown a slightly modified form of the valve operating means. In this construction the bucket 19^a is connected to one arm of a lever 21^a, the other arm of said lever carrying a valve 24^a. In this form of the device the lever is straight instead of being angular as shown in Fig. 2. The operation of the device, however, is precisely the same as that heretofore described.

What I claim is:

1. A fuel feeding apparatus comprising a fuel tank, a carburetor, a gasoline engine, a feeding tank above the level of the carburetor, a pumping chamber arranged to discharge into the feeding tank and provided with a gasoline inlet, means connecting the pumping chamber with the intake of the engine, means connecting the said chamber with the

fuel tank, a movable pump bucket within the pumping chamber, means to charge said bucket with gasoline when the accumulated gasoline rises to a predetermined height in said chamber, valve mechanism, means whereby the charged bucket will operate said valve mechanism to stop the gasoline inflow and open the pumping chamber to the atmosphere, means whereby upon opening said chamber to the atmosphere the accumulated gasoline therein will be discharged into the feeding tank, and means whereby the bucket will be emptied after the pumping chamber is discharged.

2. The combination of a feed tank, a pumping chamber having an inlet and a vent, suction operated means for accumulating fluid in said pumping chamber, a valve mechanism controlling communication between the pumping chamber and the fluid inlet, a movable pump bucket in the pumping chamber, means for charging said bucket when the fluid in the pumping chamber has reached a predetermined level, means connecting said bucket to the valve mechanism whereby when the bucket is charged the valve mechanism will be operated to open the vent of the pumping chamber and stop the flow of fluid into said chamber, and means for controlling communication between the pumping chamber and the feed tank, said last mentioned means operating to discharge the contents of the pumping chamber when said chamber is vented.

3. The combination of a feed tank, a pumping chamber having an inlet and a vent, suction operated means for accumulating fluid in said pumping chamber, a valve mechanism controlling communication between the pumping chamber and the fluid inlet, a movable pump bucket in the pumping chamber, a siphon connecting the pumping chamber with said bucket, said siphon charging the bucket when the fluid in the pumping chamber has reached a predetermined level and serving to discharge the contents of the bucket when the fluid in the pumping chamber is discharged, means connecting said bucket to the valve mechanism whereby when the bucket is charged the valve mechanism will be operated to open the vent to the pumping chamber and stop the flow of fluid into said chamber, and means for controlling communication between the pumping chamber and the feed tank, said last mentioned means operating to discharge the contents of the pumping chamber when said chamber is vented.

4. In combination with a gasoline engine having a carburetor, a gasoline tank, and means for feeding gasoline from said tank to said carburetor embodying a pump chamber provided with an outwardly-opening valve at its lower end and with an exhaust port and a vent port at its upper end, a pipe

connecting the upper end of the pump chamber to the gasoline tank and another pipe connecting the exhaust port to the intake of said engine, a single valve adapted to be shifted from the vent port to the exhaust port and vice versa, and means in the pump chamber for normally holding the valve so as to close the vent and for automatically opening the vent and closing the exhaust

port when a predetermined quantity of gasoline accumulates in the pump chamber, the suction created by the engine serving to hold the valve at the lower end of the pump chamber normally closed and also to draw gasoline into the pump chamber. 10

In testimony whereof I hereunto affix my signature. 15

HAROLD C. SUCKERT.
